UNITED STATES PATENT OFFICE.

WILLIAM A. HEILMANN, OF VAILSBURGH, NEW JERSEY, ASSIGNOR TO THE R. NEUMANN HARDWARE CO., A CORPORATION OF NEW JERSEY.

CLASP FOR BAG-FRAMES.

1,278,645.

Specification of Letters Patent. Patented Sept. 10, 1918.

Application filed May 22, 1918. Serial No. 235,946.

To all whom it may concern:

Be it known that I, WILLIAM A. HEILMANN, a citizen of the United States, residing at Vailsburgh, in the county of Essex and State of New Jersey, have invented certain new and useful Improvements in Clasps for Bag-Frames; and I do hereby declare the following to be a full, clear, and exact description of the invention, such as will 10 enable others skilled in the art to which it appertains to make and use the same, reference being had to the accompanying drawings, and to characters of reference marked thereon, which form a part of this 15 specification.

The present invention has reference, generally, to improvements in clasps for bag-frames of all kinds; and the invention relates, more particularly, to a very simple 20 clasp device for retaining the hinged members of a bag-frame in closed relation to each other.

The invention has for its principal object to provide a very cheap one-piece construction of clasp device, adapted for pivotal association with the outer member of a pair of hinged bag-frame members, so arranged that portions thereof will straddle and embrace the closed members when it is itself 30 closed or turned down over the latter, but which embracing portions will be raised clear of the bag-frame members when it is itself swung or turned upward on its pivotal connection, thus freeing the bag-frame members for opening movement. Said clasp device also having a suitable finger-piece, integrally formed therewith, whereby it may be manipulated to move the same to its clasping or unclasping relation to said bag- 35 frame members.

Other objects of the present invention, not at this time more particularly enumerated, will be clearly understood from the following detailed description of the same.

With the various objects of the present invention in view the same consists, primarily, in the novel construction of one-piece clasp device, as well as in the relation and details of the construction of its various 50 parts, all of which will be hereinafter more fully described, and then finally embodied in the appended claim.

The invention is clearly illustrated in the accompanying drawings, in which:—

55 Figure 1 is a perspective view of a pair of hinged bag-frame members, in closed relation to each other, the same being provided with a pair of the novel clasp devices, shown in said view in their operative relation to the bag-frame members for retaining the latter in closed relation to each other.

Fig. 2 is a perspective view of said hinged bag-frame members in opened relation to each other, the novel clasp devices being shown in their unclasping or released position relative to the bag-frame members.

Fig. 3 is a detail perspective view of the closed bag-frame, showing the opposite side of a novel clasp device in unclasping or released position; and Fig. 4 is a similar view 70 showing the novel clasp device in clasped or retaining position.

Fig. 5 is a detail perspective view, similar to that shown in Fig. 3, but illustrating a slightly modified construction of the novel 75 clasp device.

Similar characters of reference are employed in all of the hereinabove described views, to indicate corresponding parts.

Referring now to the said drawings, the 80 reference character 1 indicates the outer frame-section, and the reference character 2 indicates the inner frame-section of a hinged bag-frame. The said outer frame-section telescopes over or incloses the inner frame-section, when the bag-frame is closed. The said frame-sections are hinged together at their opposite ends by a pivoting means 3.

The novel clasp devices for securing the frame-sections in closed relation to each 90 other are adapted to be connected with the outer frame-section 1.

Each clasp device comprises a main body 4 adapted to extend laterally across the top surface of said outer frame-section 1. Integrally connected with one end of said main body 4 is a downwardly extending side member 5, which normally extends over the outer side portion 1' of said frame-section 1. Integrally connected with the rearward edge 8 of said side member 5, so as to lie in the same plane, is a rearwardly extending perforated tongue or lug 6, adapted to receive a pivoting rivet 7, whereby the main body 4 is pivotally connected, at a point to the 105 rear of its rearward edge 8, to said side portion 1'. Integrally connected with the opposite end of said main body 4 is a downwardly extending opposite side member 9, which normally extends over the outer side 110

portion 2' of said frame-section 2, when the latter is closed into said frame-section 1. Said main body 4, and its respective side members 5 and 9, together form an embracing member or yoke which when turned down over the closed bag-frame sections, retain the latter against separation or opening movement upon their hinged connections. Extending forwardly from the front 10 edge 10 of said main body 4 is a tongue 11 having a slightly upwardly curved free end portion 12, which serves to permit the fingers to engage the clasp device to swing the same upward to open or releasing position.

When it is desired to release the clasp device the finger piece formed by the parts 11 and 12 is engaged and lifted upwardly. This swings the main body 4 from a normal 20 horizontal plane to a vertical plane, thereby causing the side members 5 and 9 to also swing upwardly, and particularly causing the side member 9 to swing up out of obstructing position relative to the path of 25 opening movement of said inner frame section 2. Since the pivotal connection provided by the perforate tongue or lug 6 is rearwardly off-set relative to the rear edge of said main body 4, it follows that said 30 main body 4 may be moved until its movement is arrested by said rearward edge 8 engaging the top surface of the outer frame-section, the amount of off-set of the tongue or lug 6 being sufficient to permit the main 35 body 4 to attain a substantially vertical position. When finally stopped in its fully raised position the main body 4 is so moved that the side members 5 and 9 have been completely removed from embracing engagement or relation to the closed frame-sections. In order, however, to prevent 40 accidental bending or distortion of the side-member 9 by accidental blows or similar causes, which distortion might result in accidentally bending inward the side member 9 so that it could not be returned to proper 45 and normal embracing relation to the closed frame-sections, I have provided the said side member 9 with a laterally extending or 50 projecting lip 13 at its rearward edge. This lip 13, when the side member 9 has been freed from obstructing relation to said inner frame-section 2 by the upward swinging movement of the main body 4, is, nevertheless, 55 so disposed as to extend over the

edge 14 of the outer frame section 1 so as to be backed thereby, and consequently is held or backed by said edge 1 so as to provide a resistance to any accidental inward bending or distortion of said side member 10.

Usually the clasp devices are employed in pairs in connection with the bag-frame, and are consequently preferably made in right and left form as shown in the drawings, although this is not essential, being at best 65 but a matter of appearance, consequently I do not limit myself to employ such right and left form of construction only.

Referring now to Fig. 5 of the drawings, I have there shown a modification of the 70 novel clasp device. The said modification does not alter the main features of the construction, which features are indicated by the corresponding reference characters identifying the same in the main views and 75 above description thereof. The finger piece, constituted by the parts 11 and 12, however, is omitted in this modification, and the device is manipulated by grasping the sides thereof, and swinging the same upward, or 80 in any other desired manner.

It will be apparent that the novel clasp devices constructed as above described are exceedingly simple, and can be stamped or blanked out of a single sheet of metal and 85 easily bent in proper dies to properly relate and form the several parts thereof, consequently the clasp device, while very effective for the purposes intended, is, however 90 very cheap and economical and of neat appearance.

I claim:

In a device of the kind described, a main body having depending side-members, a rearwardly off set perforate ear connected 95 with one of said side-members to provide a point of pivotal attachment of said body to a bag-frame, and the opposite of said side-members having a laterally projecting holding lip at its rearward edge to overlap a 100 bag-frame edge when the main body and its said side members are raised to released position.

In testimony, that I claim the invention set forth above I have hereunto set my hand 105 this 17th day of May, 1918.

WILLIAM A. HEILMANN.
